W. H. RODEBUSH,
APPARATUS FOR PRODUCING TETRAHALOGENATED HYDROCARBONS.
APPLICATION FILED AUG. 25, 1919.

1,402,318.

Patented Jan. 3, 1922.

W. H. Rodebush, Inventor
By his Attorney, George Wright Small

UNITED STATES PATENT OFFICE.

WORTH H. RODEBUSH, OF BALTIMORE, MARYLAND, ASSIGNOR TO U. S. INDUSTRIAL
ALCOHOL CO., A CORPORATION OF WEST VIRGINIA.

APPARATUS FOR PRODUCING TETRAHALOGENATED HYDROCARBONS.

1,402,318.

Specification of Letters Patent. Patented Jan. 3, 1922.

Application filed August 25, 1919. Serial No. 319,731.

To all whom it may concern:

Be it known that I, WORTH H. RODEBUSH, a citizen of the United States, residing at Baltimore, in the State of Maryland, have 5 invented a certain new and useful Improvement in Apparatus for Producing Tetrahalogenated Hydrocarbons, of which the following is a specification.

My invention relates particularly to an 10 apparatus for producing compounds of halogens with hydrocarbons, but has relation especially to the production of acetylene tetrachloride.

The object of my invention is to provide 15 and apparatus by means of which acetylene tetrachloride or the corresponding compounds of acetylene with other halogens may be advantageously made. Another object of my invention is to provide an apparatus 20 of this character in which a high yield is obtained. Still another object is to provide an apparatus of this character which is conducted so as to avoid the escape of the reagents and the products desired formed.

25 Further objects of my invention will appear from the detailed description thereof contained hereinafter.

While my invention is capable of embodiment in many different forms, for the purpose 30 of illustration I have shown only one form of apparatus in the accompanying drawing, in which:

The figure is a diagrammatic representation 35 of an apparatus made in accordance with my invention.

In the drawing, I have shown a container 1 which is preferably made of some opaque material, that will not be acted upon by the substances present therein during the treatment. The container 1 is provided with a 40 valved inlet opening 2 preferably in its top, as shown, and suitable for the liquid materials to be introduced into the container 1, and which is provided also for the purpose 45 of permitting the insertion of a thermometer to determine the temperatures during the treatment. As above indicated, the apparatus may be utilized for producing acetylene tetrachloride, acetylene tetrabromide, or 50 acetylene tetraiodide, but I shall describe it particularly as applied to the production of acetylene tetrachloride. For this purpose, I introduce into the container 1 through the 55 valved inlet opening 2 a quantity of ethylene dichloride. After the valved inlet opening 2 has been closed, gaseous chlorine is introduced by means of an annular perforated pipe 3 located near the bottom of the container 1, so as to thereby agitate the liquid, and cause the chlorine to become dissolved 60 therein. The agitation of the liquid is augmented by the operation of mechanical means such as a propeller 4 carried by a shaft 5 in the container 1, and driven by bevel gears 6 and 7 from a driving shaft 8 65 carrying a pulley 9, which is driven from any suitable source of power. The rotation of the propeller 4 produces a downward current of the materials in the container 1, tending to cause the same to pass out 70 through an opaque tube 10, thence into a glass tube 11, and from this point by means of an opaque tube 12 back into the container 1. The circulation of the liquid in this manner is insured, however, by the presence 75 of a propeller 12^a in the tube 10. In this way, a continual circulation of the materials is obtained through the glass tube 11. In the interior of the tube 11 there is also shown a mercury vapor light 12^b to 80 provide actinic light when the light from the sun is insufficient. There is a considerable rise in temperature due to the combination of chlorine with the ethylene dichloride, so as to form acetylene trichloride and acetylene tetrachloride. The light admitted to 85 the liquid through the transparent tube 11, and the heat developed, both facilitate the union of the chlorine with the ethylene dichloride, and in this way, the production of 90 the acetylene tetrachloride is very much accelerated. During the treatment, there is an evolution of hydrochloric acid gas which passes out of the container 1 by means of a pipe 13 of a reflux condenser which is cooled 95 by means of a water jacket 14 having inlet and outlet pipes for a current of cooling water 15 and 16. The reflux condenser will condense any of the ethylene dichloride, acetylene trichloride and acetylene tetrachloride which may be vaporized during the 100 treatment. The treatment is carried out in

- 2
- this way for from 2 to 3 hours, the liquid level being preferably maintained at about the point indicated in the drawing, and above the transparent chamber, and when 5 the boiling point of the liquid has reached a temperature of approximately 104° C., the action is stopped, and the liquid is drawn off by means of a valved outlet pipe 17 located at the bottom of the container. 10 This liquid will comprise a mixture of acetylene trichloride and acetylene tetrachloride with a little ethylene dichloride, and these liquids may then be readily separated by fractional distillation. 15 It will be understood that instead of carrying out my invention in such a manner as to produce acetylene tetrachloride, ethylene dibromide may be treated by the injection of bromine in the form of a liquid or vapor 20 in order to produce acetylene tetrabromide, or ethylene diiodide may be treated with iodine in a similar manner to produce acetylene tetraiodide.
- While I have described my invention above in detail, I wish it to be understood that many changes may be made therein without departing from the spirit thereof. For example the agitator 4 and the parts used for operating the same may be entirely omitted. 30
- Although the temperature 104 degrees C. has been mentioned above, it is to be understood that other temperatures may be employed according to the circumstances of the 35 particular case and the character of the halogen. The temperatures may accordingly be varied considerably from the temperature named, and no particular temperature is deemed essential, it being within the 40 skill of those versed in the art to employ the proper temperature at which the action is to be stopped.
- I claim:
1. A chlorinating apparatus comprising a 45 tank having an inlet and outlet and a vertical reaction chamber connected thereto near its top and bottom, a source of light in the reaction chamber, an agitator at the bottom of the reaction chamber to force liquid up 50 into it, and means for injecting chlorine into the tank.
  2. A chlorinating apparatus comprising a tank having an inlet and outlet and a vertical reaction chamber connected thereto near 55 its top and bottom, an agitator in the tank operating to circulate liquid from the bottom of the tank up into the reaction chamber, a source of light in the latter, an agitator at the bottom of the reaction chamber 60 to force liquid thereinto, and means for injecting chlorine into the tank.
  3. An apparatus for halogenating, comprising a main container provided with an inlet in its upper portion and with an additional inlet for a halogen in its lower por- 65
- tion, mechanical means for the agitation of the consequent mixture to produce a downward current therein, and a transparent reaction chamber connected therewith by a plurality of tubes below the level of the liquid in said main container, whereby the mixture may be continuously circulated through the main chamber and the reaction tube, without danger of an excess of the halogen in the reaction chamber. 75
4. An apparatus for halogenating, comprising a main container provided with an inlet in its upper portion and with an additional inlet for a halogen in its lower portion, mechanical means for the agitation of the consequent mixture to produce a desired current therein, a transparent reaction chamber connected therewith by a plurality of tubes below the level of the liquid in said main container and a mercury vapor light 80 within said reaction tube, whereby the mixture may be continuously circulated through the main chamber and the reaction tube, without danger of an excess of the halogen in the reaction chamber. 85
5. An apparatus for halogenating, comprising a main container provided with an inlet in its upper portion and with an inlet for a halogen in its lower portion, mechanical means for the agitation of the consequent mixture to produce a downward current 90 therein, a transparent reaction chamber connected therewith by a plurality of tubes below the level of the liquid in said main container, and a reflux condenser connected to the top of said main container, whereby the mixture may be continuously circulated through said main container and said reaction tube, without danger of an excess of the halogen in the reaction chamber, without 95 loss of valued products. 100
6. An apparatus for halogenating, comprising a main container provided with an inlet in its upper portion and with an inlet for a halogen in its lower portion, mechanical means for the agitation of the consequent mixture to produce a downward current therein, a transparent reaction tube 110 connected therewith by a plurality of tubes below the level of the liquid in said main container, a source of light within said reaction tube, and a reflux condenser connected with said main container, whereby the mixture may be continuously circulated through the main container and the reaction tube, without danger of an excess of the halogen in the reaction chamber, without 115 loss of valued products, and until the halogenation is carried to the desired degree of completion. 120
7. A chlorinating apparatus comprising a tank having an inlet and outlet and a reaction chamber connected thereto near its top and bottom, a source of light in the reaction chamber, an agitator positioned to circulate 125

liquid from the tank through the reaction chamber, and means for injecting chlorine into the tank.

8. A chlorinating apparatus comprising a tank having an inlet and outlet and a transparent reaction chamber connected thereto near its top and bottom, an agitator posi-

tioned to circulate liquid from the tank through the reaction chamber, and means for injecting chlorine into the tank. 10

In testimony that I claim the foregoing, I have hereunto set my hand this 31 day of July, 1919.

WORTH H. RODEBUSH.
